UNITED STATES PATENT OFFICE.

WALLACE H. BATE, OF BOSTON, ASSIGNOR TO JAMES W. TUFTS, OF MEDFORD, MASSACHUSETTS.

TUMBLER-WASHER.

SPECIFICATION forming part of Letters Patent No. 252,573, dated January 17, 1882.

Application filed May 11, 1881. (Model.)

To all whom it may concern:

Be it known that I, WALLACE H. BATE, of Boston, in the county of Suffolk and State of Massachusetts, have invented certain Improvements in Tumbler-Washers, of which the following is a full, clear, and exact description, reference being had to the accompanying drawings, making part of this specification, in which—

10 Figure 1 is a perspective view of a tumbler-washer constructed in accordance with my invention. Fig. 2 is a vertical section through the center of the same.

15 My invention relates to certain improvements in tumbler-washers; and it consists in a novel combination of parts, as hereinafter set forth and specifically claimed.

20 In the said drawings, A represents a short tube or thimble, which is to be secured to the end of the supply-pipe. Into the upper enlarged end of this thimble A is screwed the body or shell B, at the lower end of which is formed a seat for the valve *a*, the spindle or stem C of which passes up through a guide, 5, 25 in the center of the body B, the valve being so arranged that the action of the water, assisted by a light spiral spring, *b*, will close it when not held open by the weight of the tumbler on the valve-spindle, as will be hereinafter de-

30 scribed. The upper end of the valve-spindle C is pointed and serves as a rest for the tumbler, the weight of which, acting through the stem C, causes the valve to be pressed down to admit the water, which then passes up 35 through a series of apertures, *d*, formed in the body B, around the guide 5, into a chamber, D, immediately beneath and within a screw-cap, E, forming the upper portion of the body B. The aperture in the top of the cap E, through

40 which the spindle C passes, is slightly enlarged, so as to form an annular orifice, *f*, through which the water is discharged vertically against a distributer, G, consisting of a series of curved blades, *g*, attached to a collar, *h*, which 45 encircles the spindle C, and is free to revolve thereon, with the blades, when the latter are acted upon by the water discharged from the annular orifice *f*.

The spindle C is made in two parts, screwed 50 together at *i*, the portion of the spindle on

which the distributer revolves being of less diameter than the adjacent portions, in order that the distributer may be held securely in place. When the water is projected against the distributer G it is deflected thereby, and impinging against the interior of the tumbler causes it to revolve on the apex or point of the valve-stem C, by which it is supported, and in this manner the water is thoroughly scattered in all directions and brought into contact with all portions of the interior of the tumbler, thus thoroughly cleansing it, as required.

The distributer G may be securely attached to the spindle C, so as not to revolve thereon; but I prefer to have it rotate, as it distributes 65 the water with better effect and attracts attention by its movement.

The annular aperture *f* is not liable to become clogged; but if obstructed it can be readily cleared by removing the cap E, without the employment of any tool or instrument whatever. Furthermore, less water is required, as after the tumbler has been washed the flow of water can be greatly reduced, so as to use only just sufficient to rotate the distributer G 75 for the purpose of attracting attention, this rotation of the distributer giving the tumbler the appearance of revolving, when it is really stationary.

I do not confine myself to the employment 80 of an annular discharge-orifice, *f*, for the water in connection with the distributer, as it is evident that a discharge orifice or orifices of other form may be used. For instance, the valve-stem may be made hollow for the passage of 85 the water, and provided with one or more apertures adapted to discharge the water against the distributer; but I prefer the construction just described, as it is more simple.

I am aware of the United States Letters Patent granted to J. C. Wharton, September 29, 1868, and to E. W. Russell, December 31, 1867, and therefore make no broad claim to a revolving water-distributer, nor to a vertical valve-spindle on which the tumbler is placed 95 and by which it is depressed to open the valve; but

What I claim as my invention, and desire to secure by Letters Patent, is—
In a tumbler-washer, the combination of the 10

shell or body B, having a discharge orifice or orifices, a valve-spindle, C, working vertically through the shell of the valve and serving as a support upon which the tumbler revolves, 5 and a revolving distributer, G, adapted to intercept the water issuing from the discharge orifice or orifices and deflect it against the interior surface of the tumbler, substantially as and for the purpose described.

Witness my hand this 9th day of May, A. D. to 1881.

WALLACE H. BATE.

In presence of—

P. E. TESCHEMACHER,
W. J. CAMBRIDGE.
